(57) **CLAIM**

The ornamental design for an armchair with stool set, as shown and described.

DESCRIPTION

FIG. 1 is a front, right top perspective view of an armchair with stool set, consisting of an armchair and a stool with legs, showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a front, right, top perspective view of the armchair, shown separately for ease of illustration.

FIG. 9 is a front, right, top perspective view showing, the stool without legs, under the armchair.

FIG. 10 is a front, right, top perspective view of the stool with legs, shown separately for ease of illustration; and, FIG. 11 is a perspective view of the stool without legs, shown separately for ease of illustration.

The broken lines shown in the drawings depict portions of the armchair with stool set that form no part of the claimed design.
